ELECTRIC FIXTURE

Isaac Litner, Brooklyn, N. Y., assignor to Bright
Light Reflector Co. Inc., Kings County, N. Y.

Application October 7, 1936, Serial No. 104,427

4 Claims. (Cl. 173—358)

This invention relates to electric fixtures, and particularly to structures of this general category comprising two units adapted to be mechanically and electrically joined together.

It is the usual practice in assembling two electric units of certain types, such as a reflector with a socket and an electric outlet fixture, to manually connect the wiring terminals and attach the parts together by suitable tools, requiring a similar but reverse procedure for detaching the parts. It is one of the objects of my invention to facilitate the assembling of such units by enabling them to be secured together without the use of any tools whatsoever and to simultaneously effect a proper electrical union.

It is also within the contemplation of my invention to enable two units of the aforesaid class to be readily and firmly secured together in proper assembled relation by a simple manual manipulation, and to enable a similar ready detachment of the parts.

And it is a further object of my invention to provide an electric fixture possessing the above-stated advantages and so constructed as to be durable, simple in construction and inexpensive to fabricate.

Other objects, features and advantages will appear from the drawing and the description hereinafter given.

Referring to the drawing,

Figure 1 is a perspective view of the two units, shown detached, which constitute one form of my invention as applied to a lighting fixture.

Figure 2 is a bottom view of the upper portion or wiring terminal unit constituting part of my invention.

Figure 3 is a plan view of the lower portion or connector unit constituting another part of my invention.

Figure 4 is a vertical sectional view of the two units constituting my invention taken along lines 4—4 of Figures 2 and 3 in their proper assembled relation, and

Figure 5 is a fragmentary section of Figure 2 taken along line 5—5, showing the housing with the wiring block removed.

In the drawing, the wiring terminal unit 6 contains as an element thereof the housing 7 adapted to be attached to a wall, ceiling or other structure containing electrical conductors 8. Centrally positioned within the housing is the block 9 serving as the upper contact unit adapted for operative engagement with the lower contact unit 13 to be hereinafter described. The said block 9 contains the wiring terminals 10 and the contacts 11 electrically joined to the conductors 8.

The connector unit 12, shown in the drawing for the purpose of illustration as a reflector, comprises the lower contact unit 13, including the

body portion 14 housing an electrical socket, the contacts 15 and the electric terminals 16.

Both contact units 9 and 13 contain enlarged portions, preferably in the form of flanges, the upper unit containing the flange 17 and the lower unit the flange 20. Encircling both units are the annular ring-like members 18 and 19, the former being preferably loosely mounted over the block 9 and underlying and in supporting engagement with the flange 17, and the latter being affixed to the flange 20 by screws 21 and 22 extending through the inwardly bent flanged base 23 of the shade 24,—the said base being supported by the flange 20 of the lower contact unit.

Both of the annular members 18 and 19 contain a plurality of peripheral extensions substantially radially disposed, the said extensions of the member 18 being identified by the numerals 25, 26 and 27, and those of the member 19 by the numerals 28, 29 and 30.

The internal wall of the housing 7 contains horizontal and preferably annular ridges 31 and 32, the former for supporting the extensions 28, 29 and 30 of the annular element 19 and the latter for supporting the extensions 25, 26 and 27 of the upper annular member 18. The said annular ridges are interrupted by lower openings or recesses 33, 34 and 35, and upper openings or recesses 36, 37 and 38, these being made to correspond with the aforementioned extensions to permit of their vertical passage therethrough. A section of the upper ridge 32 is separated from the recess 36 by the wall 39, and from the recess 37 by the stop or screw 40 which extends through the wall of the housing and is retractable therefrom. The helical spring 41 is in yieldable engagement with the upper inner surface of the housing and the block 9, normally tending to urge the latter downwardly.

In assembling the two units constituting this device, the lower connector unit 12,—shown as the reflector unit,—is moved upwardly into operative engagement with the wiring terminal unit 6,—the extensions 28, 29 and 30 of member 19 being moved through the recesses 33, 34, and 35 until contact is made between contact units 9 and 13. Upon continued upward pressure, against the action of spring 41, the annular member 19 is brought above the level of the elevated portion 42 of the ridge 31, and then the entire connector unit is given a turn so that the extension nearest said elevated portion 42 passes thereover, the rotary movement continuing with the extensions 28, 29 and 30 moving over or slidably moving along the ridge 31 until the desired position is obtained. Upon a release of the connector unit, the pressure caused by the spring 41 will actuate the block 9 downwardly, through the central opening of annular member 18, to effec-

tuate a firm engagement between the adjacent contacts 11 and 15,—simultaneously causing the extensions 28, 29 and 30 of the annular ring 19 to bear firmly down against the ridge 31 and thereby establish a rigid assembly.

5 In this way it is seen that by a simple upward and rotary movement of the connector member, and its attached parts, a firm mechanical connection is secured between the upper and lower 10 units as well as an electrical union of the conductors. No tools are necessary, and no individual attachment of wires is required.

To effect a detachment of the parts, the lower 15 connector unit is simply forced upwardly against the pressure of the spring to a position above the elevated portion or stop 42, and then rotated until the extensions 28, 29 and 30 are in registry with the openings 33, 34 and 35, and then drawn down vertically to completely detach the units. Thus it

20 will be seen that an electric fixture containing two separate units embodying my invention can also be disassembled by a simple manual manipulation without the use of any instruments and without disturbing the fixed wiring connections.

25 There is no possibility of the connector unit becoming detached due to jarring, shocks or vibration, as the elevated portion 42 and the wall 45 prevent a movement of the member 19 and attached parts beyond desired limits.

30 In assembling the elements of the upper wiring terminal unit 6, the block 9 and the annular member 18 mounted thereover, are inserted within the housing 7 by actuating them upwardly against the spring 41, the extensions 25, 26 and 27 being

35 moved vertically through the openings 36, 37 and 38,—and then turning the loosely mounted member 18 until the extensions thereof rest upon the ridge 32. In inserting the said member 18, it is first necessary to retract the screw 40 to leave the

40 passageway clear for the adjacent extension of the member to move therewith. After the member 18 is in its proper position, the screw 40 is actuated inwardly to hold the member 18 against rotation and particularly against such movement, due to 45 jarring or vibration, as might cause the extensions of this plate to move towards and over the recesses 36, 37 and 38 and drop therethrough. The wall

39 together with the shank of screw 40 serve to prevent the extension of the member 18 which is 50 positioned therebetween from moving therebeyond, serving as stops at the recesses or openings 36 and 37. As aforesaid this prevents a dropping down of the wiring terminal 9 when the connector unit is disengaged.

55 It should be noted, in the form of housing shown in the drawing, that the ridge 43 at the bottom of the dome of the housing forms, together with ridge 32, a channel 44 within which the extensions of the member 18 can move. Furthermore, in 60 inserting the said member, the said ridge 43 prevents an upward movement thereof beyond the upper limit of the channel. If, however, there is no such ridge, as is the case in many housings of different designs, and the screw 40 is not in its retracted position, the member 18 can nevertheless be properly inserted by forcing it upwardly until the extensions on the member 18 are elevated above the shank of the screw 40 and then the parts rotated to bring it into proper position.

70 It is of course understood that the various embodiments above described and shown in the drawing are illustrative of my invention and not

employed by way of limitation, inasmuch as numerous changes and modifications may be made within the scope of the appended claims without departing from the spirit of this invention.

What I claim is:

1. In an electric fixture terminal, a housing, supply wires, an insulated block carrying at its lower end contact members to which the supply wires are attached, said block having a smooth peripheral wall and a projecting flange, an annular plate loosely surrounding said block and underlying said flange, the edge of said plate having projections which engage abutments within the housing, a connector unit comprising a body portion having contacts engageable with the contact members of said block, a second plate secured to said body portion and having extensions engaging abutments within said housing in spaced relation to said first mentioned plate, and a spring bearing against said housing and said block to firmly hold the flange of said block against said first mentioned plate. 10 15

2. The combination of claim 1 wherein the internal wall of said housing is provided with an annular rib engaged by said first mentioned plate and a second annular rib engaged by said second plate each of said ribs having cut away portions at points corresponding to the projections of said plates, the respective cut away portions of said ribs being in vertical alinement to provide channels through which the projections on said first mentioned plate may be moved straight into its position above said first mentioned annular rib. 25 30

3. The combination of claim 1 wherein the internal wall of said housing is provided with an annular rib engaged by said first mentioned plate and a second annular rib engaged by said second plate each of said ribs having cut away portions at points corresponding to the projections of said plates, the respective cut away portions of said ribs being in vertical alinement to provide channels through which the projections on said first mentioned plate may be moved straight into its position above said first mentioned annular rib, and stop means carried by said housing to limit 45 rotational movement of said first-mentioned plate. 35 40

4. In an electric fixture, a wiring terminal unit and a connector unit detachably secured thereto, the terminal unit containing a housing and a block provided with wiring terminals and contacts, the connector unit containing a body portion provided with contacts and electric terminals, flat independent annular members mounted on and adapted to support said block and said body portion, respectively, and having radial extensions thereon, the internal wall of the housing containing annular ridges at two levels with a plurality of recessed portions corresponding to said extensions and adapted to permit the extensions 55 to pass therethrough, the upper of said ridges being adapted to slidably support the extensions of the annular member on the said terminal unit, and the lower of said ridges to slidably support the extensions of the annular member on said 60 connector unit, and spring means urging said terminal unit into operative engagement with said connector unit whereby the adjacent contacts are held in abutment, the upper of said members being loosely mounted on said block and movable 65 with respect thereto. 70

ISAAC LITNER.
